UNITED STATES PATENT OFFICE.

JOHN J. A. MILLER, OF DENVER, COLORADO, ASSIGNOR TO THE AUTOMATIC FURNACE OXIDATOR AND MANUFACTURING COMPANY, OF DENVER, COLORADO, A CORPORATION OF COLORADO.

AUTOMATICALLY-OPERATING OXIDATOR FOR ATTACHMENT TO FURNACE DOORS FOR ABATING SMOKE.

Application filed October 9, 1922, Serial No. 593,475. Renewed March 31, 1926.

My invention relates to improvements in automatically operating oxidators for attachment to furnace doors for abating smoke.

5 The object of the invention is to provide an attachment for the doors of furnaces, comprising a shutter controlled air heater and automatically operating mechanism for operating the shutters, by which the shutters 10 are opened simultaneously with the closing of the door to permit air to enter the furnace through the air heater, means being connected with the shutter operating mechanism for gradually closing the shutters with- 15 in a predetermined period.

Further, to provide in connection with the shutter operating mechanism of oxidators or smoke abating attachments of this character, a gravity operated oil controlled piston, 20 which is raised in an oil cylinder by said shutter operating mechanism simultaneously with the opening of the shutters, the length of time required for the descent of said piston, and consequently for the closing of the 25 shutters, being determined by an adjustable valve in said piston, which permits the free upward stroke of the piston through the oil, but retards its descent, said shutters permitting a regulated supply of air through the 30 heater to the furnace for a given period after the coaling operation, the said air being discharged over the coal bed, by which it is mixed with the combustible gases and floating particles of carbon and tar, thus causing 35 complete combustion of these particles and the consequent elimination of smoke.

These objects are accomplished by the mechanism illustrated in the accompanying drawings, in which:

40 Fig. 1 is a front view of a furnace door equipped with the improved device;

Fig. 2 is a top view, partly in section, of Fig. 1, the cap of the housing being removed;

45 Fig. 3 is an enlarged vertical sectional view of the housing on the line 3-3 of Fig. 1;

Fig. 4 is an enlarged sectional view on the line 4-4 of Fig. 1;

50 Fig. 5 is a plan view of a portion of the door provided with the improved device, the door being partly open, and

Fig. 6 is a front view of the air pre-heater. Visible furnace smoke can be abated only by effecting complete combustion in the furnace, of the floating particles of carbon and tar, and this can be accomplished only by supplying air sufficient for the complete oxidation of all combustible matter, and the intimate mixing of the air with the combustible gases and the floating particles of carbon and tar. To bring about this result, air in large quantities should be admitted over the fire immediately after coaling, and this quantity should be gradually reduced as the distillation of the volatile combustible nears completion.

The improved furnace door attachment is adapted to meet these requirements, by means of a combination of elements, which are arranged and constructed as follows:

Referring to the accompanying drawings: The numeral 1 indicates the front wall of an ordinary furnace, and 2 the fire door which is hinged to the furnace in the usual manner, and to which the present invention is secured.

The door is provided with a circular opening 3, which is about ten inches in diameter, and an improved air pre-heater is bolted to the back of the door to register with the opening 3. The pre-heater comprises a plurality of spaced rectangular outwardly flaring metal frames 4, arranged one within the other, and connected to form an integral structure by radial webs 5, which extend between and connect each two frames, as clearly shown in Figure 6.

The frames increase in depth progressively from the outer frame, which is about five inches in depth, to the innermost frame 6, which is practically a rectangular tube. Apertured lugs 7 are formed on the smaller end of the outer frame 4 and bolts 8 are passed through these lugs and through the door, and through lugs 9 on a rectangular frame 10 on the front side of the door, thus securing both the pre-heater and the frame 10 to opposite sides of the door.

The outer frame of the pre-heater is about five inches in depth, and the remaining frames increase in depth progressively toward the innermost frame or tube 6, which is the deepest. When the furnace door is

closed, the pre-heater extends in, over and above the coal bed of the furnace and is thus heated to a high degree of temperature, so that atmospheric air passing through it into the furnace is highly heated in passing through the said pre-heater, as will be understood.

The width of the frame 10, from side to side is the same as the diameter of the hole 3 in the door. This frame is provided with a series of overlapping shutters 11 in the form of thin metal blades having apertured lugs 12 on their opposite ends and centrally of their widths, to receive pivot pins 13, which are mounted in two opposite sides of the frame.

The central shutter has a lug 12 on one end only, and upon the opposite end of this shutter is riveted the bifurcated end of a shaft 14, which extends through the adjacent side of the frame 10, and through the adjacent side of a housing 15, which is secured to the frame 10 and to the front side of the furnace door, as will later appear. The shutters 11 are connected to turn in unison by a flat connecting rod 16, which lies between pairs of ears 17 on the shutters, and is pivotally connected to each pair of ears. When the central shutter is turned by the shaft 14, in a manner to be presently described, the other shutters are also turned through their connection with the rod 16.

The housing 15 is divided into two chambers 18 and 19, by a partition 20, which extends far enough above the bottom of the housing to provide a bearing for the free end portion of the shaft 14, which passes through it. The housing is provided on the side next the furnace door and on the side next the frame 10, with bosses 21, which define a space between the housing and the door and between the housing and the frame 10, and bolts 22 pass through the bosses and the door on one side of the housing, and through the bosses and the frame 10 on another side of the housing, by which the housing is firmly secured to the frame 10 and to the door. The bosses prevent the housing from contact with both the door and frame, and permit the circulation of air between these parts, thus keeping the housing from becoming unduly heated.

An oil holding cylinder 23 depends from the bottom of the chamber 18 and opens into the said chamber at its upper end. A hollow piston 24 is mounted in this cylinder, the lower end wall of which is provided with a circular axial hole 25, and its upper end is formed with four radial arms or spokes 26, to which are integrally connected an upwardly projecting axial hub 27, in which is inserted the reduced portion of a piston rod 28, in the form of a rack bar, having annular teeth 29, the bar 28 being held in the hub by a pin 30, which passes through the hub

and through a groove in the said reduced portion of the rack bar, or piston rod, as it will hereafter be termed.

The piston rod has an axial hole 31 extending through the same, the lower portion of which is threaded, and a stem 32 is screwed into this threaded portion of the hole and extends through the hole 25 in the bottom of the piston.

The portion of the stem projecting below the bottom of the piston is reduced in diameter, as shown at 33, to form a shoulder 34 at the junction of the two diameters, and a disk valve 35, having an axial hole, is slipped on the reduced portion 33 and is normally held against the shoulder 34 by a spiral coil spring 36, which surrounds the reduced portion of the stem and is held in place by a pin 37, which passes through the reduced portion and engages the bottom coil of the spring. The housing is closed by a cap 38 having a threaded hole 39 in line with the hole 31 in the piston rod, which is normally closed by a screw 40. The upper end of the stem 32 is formed with a screw driver slot, and by passing a screw driver down through the hole 39 in the cap and into the hole 31 in the piston rod, the valve stem 32 may be adjusted to vary the distance between the disk valve 35, and the end wall of the piston, by which the period required for the piston to make its downward stroke through the oil in the cylinder may be lengthened or shortened to meet requirements, for a reason to be later set forth, and the spring 36 permits the disk valve to move down or away from the opening 25 under the pressure of the oil when the valve is raised, so as to permit free passage of the oil through the piston.

The shaft 14 has rigidly mounted thereon a segment gear 41, which meshes with the toothed piston rod 28, and when the shaft is turned to open the shutters 11, in a manner to be presently described, the gear 41 acts to raise the piston, and when the piston descends, the shaft 14 is thereby turned to close the shutters.

A boss 42 is formed on the outer face of the front of the housing, centrally of the width of the chamber 19, and near the upper end of the same, and this boss is formed with a threaded aperture which extends through the said front wall and into which is screwed the reduced threaded portion of a knob or knob-like casting 43. The threaded portion of the knob has a still further reduced inwardly projecting hub portion 44, and an axial bore 45 extends into the knob from its hub end to within a slight distance of its outer end. In the bore 45 is mounted the rear portion of a round slide bar 46, the forward portion of which projects through a hole 47 in the back wall of the housing, and through a hole 48 in the

door and its forward end is of conical form and when the door is closed bears against the front wall of the furnace and close to the side margin of the coal opening A therein, which is normally closed by the said door. A pin 49 extends through the bar 46, about midway of its length, and a coil spring 50 surrounds the bar and the hub portion 44 of the knob 43 and is held under compression between the pin 49 and the end of the threaded portion of the knob, when the door is closed.

A cylindrical slide block 51, having annular gear teeth 52, is mounted on the bar 46, and this block meshes with a segment gear 53, which is rigidly secured upon the shaft 14, the said shaft being below the bar as shown by Fig. 3.

When the piston is at the limit of its downward stroke, the gear 53 has moved the block 51 rearward on the bar 46, until its rear end engages the pin 49, and the parts remain in these positions as long as the door is closed.

The right hand marginal edge of the coal opening A in the furnace wall, is formed with a recess 54, having an inclined bottom which slopes up from the edge of the opening and this recess lies in the path of the conical end of the slide bar 46. When the door is closed, the said conical end of the bar engages the incline 54, by which the bar is slid back to the position shown in Fig. 3 and bears against the wall just beyond the highest point of the incline.

In operation, when the furnace door is opened, as for coaling, the conical end of the slide bar 46 is released from engagement by the furnace wall, and the said bar is projected by the spring 50, which bears against the pin 49 in said bar. The toothed slide block 51 also engages the pin 49 on the opposite side from the spring 50, and therefore the said slide block is moved forward with the bar until it engages the rear wall of the housing, thereby turning the small segment gear 53, by which the shaft 14 is also turned to open the shutters 11 to permit air to enter the furnace through the pre-heater, while the segment gear 41, which meshes with the toothed piston rod 28, raises the piston 24 to the limit of its upward movement. After the coaling, the furnace door is closed thereby bringing the conical end of the slide bar 46 into engagement with the incline 54, as previously described, by which the bar is moved back to the position shown in Fig. 3 thereby compressing the spring 50.

The slide block 51, however, is not carried back with the bar, but when the bar moves back, instantly the pin 49 releases the slide block which is then gradually slid back on the bar by the descent of the piston 24, whose toothed rod 28 turns the segment gear

41, shaft 14, and segment gear 53, which latter gear slides the block 51 back until it engages the pin 49. The turning of the shaft 14 gradually closes the shutters 11 and the time occupied by the piston in descending from its highest to its lowest position is determined by the adjustment of the valve with respect to the bottom of the piston. The bottom of the cylinder 23 is provided with a drain hole which is normally closed by a screw 55.

Having described my invention, what I claim as new and desire to secure by Letters Patent, is:

1. In a device of the character described, the combination with a furnace door, a pre-heater thereon and shutters for permitting air to enter the furnace through the pre-heater, of a spring-actuated bar which is projected when the door is opened, mechanism including a slideable member operated by said bar to open the shutters simultaneously with the opening of the door, means to reverse the movement of the bar when the door is closed, thereby releasing the slideable member, and means to reverse the movement of the mechanism to close the shutters.

2. In a device of the character described, the combination with a furnace door, an air heater thereon and shutters for permitting air to enter the furnace through the heater, of a gravity device, mechanism including a slideable member connected with the gravity device and with said shutters, a spring-actuated slide bar which is projected simultaneously with the opening of the door, to operate the mechanism whereby the shutters are opened and the gravity device raised, and means to reverse the slide bar when the door is closed thereby releasing the slideable member, whereby the mechanism is then actuated by the gravity device to gradually close the shutters.

3. In a device of the character described, the combination with a furnace door, an air heater thereon, and connected pivoted shutters for admitting air to the furnace through said heater, of a gravity-actuated oil-controlled piston, gearing connected with the piston and with one of said shutters, a spring-actuated slide bar which is projected simultaneously with the opening of the door, to operate the gearing, whereby the shutters are opened and the piston raised, and means whereby the slide bar is reversed when the door is closed thereby releasing the gearing which is then actuated by the gravity-actuated piston to gradually close the shutters.

4. In a device of the character described, the combination with a furnace door, an air heater thereon and connected pivoted shutters for admitting air to the furnace through the heater, of a gravity device, mechanism connected with the gravity de-

vice and with one of said shutters, a spring actuated slide bar which is projected simultaneously with the opening, means connected with the mechanism and movable with the bar when it is projected, whereby the mechanism is operated to open the shutters and raise the said gravity device, and means whereby the slide bar is reversed when the door is closed thereby releasing the slide-bar-operated means and permitting the gravity device to reverse the said mechanism and gradually close the shutters.

5. In a device of the character described, the combination with a furnace door, an air heater thereon and connected pivoted shutters for admitting air to the furnace through the heater, of an oil-controlled, gravity actuated valved piston, mechanism connected with one of the shutters and with 10 the piston, a spring-actuated slide bar which is projected simultaneously with the opening of the door, a block slideable on the bar and moved with the bar when the same is projected, said block being connected 15 with the mechanism whereby the same is operated to open the shutters and raise the piston; means whereby the bar is reversed when the door is closed, thereby releasing the block and permitting the piston to reverse the mechanism whereby the shutters are gradually closed, and the slide block moved to its former position on the slide bar.

6. In a device of the character described, 20 the combination with a furnace door, an air heater thereon, and connected, pivoted shutters for admitting air to the furnace through said heater; of a housing on said door having a depending oil holding cylinder, a valved piston in said cylinder having a toothed piston rod, a shaft mounted in the housing which is connected at one end with the axial portion of one of the shutters, a gear on the shaft in mesh with the toothed piston rod, a spring-actuated bar mounted in the housing which is projected beyond the rear wall of the housing 25 simultaneously with the opening of the door, a block slidably mounted on the bar, having annular teeth and movable with the bar when the same is projected, a gear on the shaft in mesh with the toothed block, whereby when the bar is projected the shaft is turned to open the shutters and lift the piston, and an incline on the furnace 30 wall which is engaged by the end of said bar when the door is closed, whereby the bar is retracted and the slide block released permitting the piston to descend to gradually close the shutters and restore the slide block to its former position on the slide bar.

7. In a device of the character described, 35 the combination with a furnace door, an air heater thereon, and a series of connected

pivotedly mounted shutters for admitting air to the furnace through said heater; of a housing secured to the door and spaced therefrom, having a depending oil holding cylinder, a piston in said cylinder having an adjustable valve and a toothed piston rod, a shaft mounted in said housing which is secured at one end to the axial portion of one of said shutters, a gear thereon in mesh with the toothed piston rod, a bar 40 slidably mounted in the housing and extending through the rear wall of the housing and through the door to engage said furnace wall, an abutment on the bar, a spring surrounding said bar and under compression between the abutment and the front wall of the housing for projecting said bar when the door is opened, a block slidably mounted on the bar, having annular teeth, and in normal engagement with said abutment, and a gear on said shaft in mesh with said toothed block, whereby when the bar is projected, the shaft is turned to open the shutters and raise the piston, and an incline on the furnace wall which is engaged by the end of the bar when the door is closed whereby the bar is retracted and the slide block released permitting the piston to gradually descend and close the shutters and restore the slide block to its former position on the slide bar.

8. In a device of the character described, the combination with a furnace door, an air heater thereon, connected pivotedly mounted shutters on the door for admitting air to the furnace through the heater, and a shaft connected to one of said shutters for turning the same; of a housing secured to said door but spaced therefrom, into which said shaft extends a knob-like casting which is screwed into the front wall of the housing, having an axial bore, a spring-actuated slide bar mounted in said bore, and extending through the rear wall of the housing and through the door, its front end being in normal engagement with the wall of the furnace, said bar being projected when the door is opened, a slide block mounted on the bar, having annular teeth, an abutment pin in said bar for defining the rearward movement of the slide block, and for carrying the slide block forward to engage the rear wall of the housing when the bar is projected, a gear on said shaft in mesh with the slide block, whereby the shaft is turned to open the shutters when the bar is projected, an incline on the furnace wall for engaging the bar to retract the same when the door is closed, whereby the slide block is released, and a gravity device connected with the shaft for gradually closing the shutters.

9. In a device of the character described, the combination with a furnace door, an air heater on the inner side of the door, a frame 130

on the front side of the door, shutters pivotally mounted in said frame and connected to turn in unison, and a shaft connected to the axial portion of one of said shutters; of spring operated slideable means and mechanism connected therewith for opening the shutters simultaneously with the opening of the door, and an oil-controlled gravity device connected with the mechanism for gradually closing the shutters after the door is closed.

10. In a device of the character described, the combination with a series of connected pivoted shutters and mechanism for opening said shutters; of means for closing the shutters comprising a gravity actuated oil-controlled hollow piston connected with said mechanism, having an open upper end pro-

vided with an axial hub having a threaded bore, and a lower end wall provided with an axial hole, a stem threaded to said bore and extending down through said axial hole, the portion of the stem below the bottom wall of the piston being reduced to form a shoulder, a disk valve on the reduced portion of the stem, a pin in said reduced portion, and a spiral coil spring interposed between the pin and the disk valve to hold the valve against said shoulder, said disk valve being of greater diameter than the hole in the bottom of the valve, said valve being adjusted with respect to the said hole by turning said stem in the said hub.

In testimony whereof I affix my signature.

JOHN J. A. MILLER.
